VALVE OPERATED VARIABLE REACTOR

Luis Charles Stenning, Park Hill, Ealing, England, assignor to The General Electric Company Limited, London, England

Application September 6, 1941, Serial No. 409,913
In Great Britain September 30, 1940

3 Claims. (Cl: 178—44)

This invention relates to variable reactors of the type wherein the effective value of the reactance of an impedance element, across which an oscillating voltage of a determinate frequency $p/2\pi$ is applied, is varied by adjusting the mutual conductance of a thermionic valve connected to the element.

In the accompanying drawing:

Figure 1 is a generalised circuit arrangement, Figure 2 is a circuit arrangement of an embodiment of the invention, and

Figure 3 shows a modification of a portion of Fig. 2.

Most, if not all, variable reactors of the type above specified are special cases of the generalised circuit arrangement shown in Figure 1. Here A and B are each a four-terminal network, having input terminals 1, 2 and output terminals 3, 4; the networks are connected by connecting their corresponding terminals each to each; the combination is used as a two-terminal network (which is the variable reactor) by applying to the terminals 1, 2 an oscillating current of a determinate frequency.

An object of this invention is to provide an improved form of variable reactor of the general type shown in Figure 1.

Referring to Figure 1, let γ_{11} , γ_{21} , γ_{22} be the input, transfer, and output admittance of A when connected to B. Let B be, or be equivalent to, a potentiometer of ratio P across the terminals 1, 2 feeding a valve with mutual conductance g_m , whose output feeds a transformer of step-down ratio ϕ . Then it is known that, if γ is the admittance of the variable reactor,

$$\gamma = \gamma_{11} + P g_m \phi \frac{\gamma_{21}}{\gamma_{22}} \quad (1)$$

If the variable reactor is to be a pure reactance,

$$P g_m \phi \frac{\gamma_{21}}{\gamma_{22}}$$

must be imaginary as well as γ_{11} . Since g_m is real, either P or $\phi \gamma_{21}/\gamma_{22}$ must be imaginary but not both.

According to this invention, in a variable reactor of the type specified operating on the principle hereinbefore described with reference to Figure 1, the said potentiometer ratio P is substantially real, and the said ratio $\phi \gamma_{21}/\gamma_{22}$ is approximately a pure imaginary. Preferably the ratio is imaginary owing to the presence in the path through the four-terminal network A of a coupling by means of mutual inductance or capacity.

The invention will now be explained further with reference to Figure 2, which shows by way of example one embodiment of the invention.

In Figure 2, L_1 is an inductor across which the oscillating voltage V of frequency $p/2\pi$ is applied. It will usually be part of a parallel tuned circuit of natural frequency near $p/2\pi$, and be in parallel with a condenser C_1 . The potentiometer P enclosed in the dotted rectangle 1, consists of condensers C_3 and C_4 in series; C_4 will often be the input capacity of the valve hereafter mentioned. The ratio P is $C_4/(C_3+C_4)$. The capacity of this potentiometer must be added to that of C_1 in tuning L_1 .

15 The voltage across C_4 is applied to the input of a valve 2 provided with means 3 for varying the grid bias and thereby the mutual conductance of the valve. Elements 2 and 3 enclosed in dotted rectangle 4 represent g_m in Figure 1.

20 The dotted rectangle 5 represents the four-terminal network A in the said Figure 1, but includes also the transformer ϕ which is effectively present, according to well known principles, in the (incomplete) band-pass filter constituted by the contents of rectangle 5. These contents, in addition to L_1 , are the inductor L_2 , condenser C_2 , and resistor R_2 in parallel, tuned to the frequency $p/2\pi$. If the valve 2 has appreciable output admittance, this is included in R_2 . The mutual inductance of L_1 and L_2 is M.

25 Then, according to known principles, at the frequency $p/2\pi$

$$\gamma_{11} = \frac{1}{j p L_1} \quad (2)$$

$$\phi \gamma_{21} = \frac{M}{j p L_1 L_2} \quad (3)$$

$$\gamma_{22} = 1/R_2 \quad (4)$$

$$\gamma = \frac{1}{j p L_1} + P g_m \cdot \frac{M R_2}{j p L_1 L_2} \quad (5)$$

$$= \frac{1}{j p L_1} \left(1 + P g_m \cdot \frac{M R_2}{L_2} \right) \quad (6)$$

Hence if $\gamma = \gamma_0 + \delta\gamma$, where $\delta\gamma$ is the part of the reactance γ which varies with g_m ,

$$\frac{\delta\gamma}{\gamma_0} = P g_m \frac{M R_2}{L_2} \quad (7)$$

In the modification shown in Figure 3, the mutual inductance M of Figure 2 is replaced by a condenser of capacity C_5 connecting the upper

ends of L_1 and L_2 . Then by an analogous argument,

$$\frac{\delta\gamma}{\gamma_0} = Pg_m\omega^2 C_6 L_1 R_2 \quad (8)$$

I claim:

1. A variable reactor of the type comprising an impedance element and a thermionic valve connected thereto and means for varying the mutual conductance of said valve, in which the effective value of the reactance of said element is varied by adjusting the mutual conductance of said valve, said reactor having a first and a second four-terminal network connected together by connecting their corresponding input and output terminals each to each and serving as a two-terminal network when an oscillating voltage of a determinate frequency is applied across said input terminals, said first four-terminal network being constituted by a step-down transformer comprising a primary inductor and a secondary inductor coupled together and each being tuned by a capacity connected in shunt to resonate at the frequency of the applied oscillating voltage, said second four-terminal network comprising a potentiometer connected across the input terminals thereof, a thermionic valve, and means for varying the mutual conductance of said valve, the input and output terminals of said valve being connected with respectively a tap on the said potentiometer and an output terminal of the said networks, and the arrangement being such that the product of the step-down ratio of said transformer and the ratio of the transfer admittance to the output admittance of said first network, when so connected to said second network, is approximately a pure imaginary quantity.

2. A variable reactor of the type comprising an impedance element and a thermionic valve connected thereto and means for varying the mutual conductance of said valve, in which the effective value of the reactance of said element is varied by adjusting the mutual conductance of said valve, said reactor having a first and a second four-terminal network connected together by connecting their corresponding input and output terminals each to each and serving as a two-terminal network when an oscillating voltage of a determinate frequency is applied across said input terminals, said first four-ter-

5 minal network being constituted by a step-down transformer comprising a primary inductor and a secondary inductor coupled together by means of mutual inductance, said second four-terminal network comprising a potentiometer consisting of two condensers connected in series across the input terminals thereof, a thermionic valve, and means for varying the mutual conductance of said valve, the input and output terminals of said valve being connected with respectively a tap on the said potentiometer and an output terminal of the said networks, and the arrangement being such that the product of the step-down ratio of said transformer and the ratio of the transfer admittance to the output admittance of said first network, when so connected to said second network, is approximately a pure imaginary quantity.

10 3. A variable reactor of the type comprising an impedance element and a thermionic valve connected thereto and means for varying the mutual conductance of said valve, in which the effective value of the reactance of said element is varied by adjusting the mutual conductance of said valve, said reactor having a first and a second four-terminal network connected together by connecting their corresponding input and output terminals each to each and serving as a two-terminal network when an oscillating voltage of a determinate frequency is applied across said input terminals, said first four-terminal network being constituted by a step-down transformer comprising a primary inductor and a secondary inductor coupled together by means of a condenser, said second four-terminal network comprising a potentiometer consisting of two condensers connected in series across the input terminals thereof, a thermionic valve, and means for varying the mutual conductance of said valve, the input and output terminals of said valve being connected with respectively a tap on the said potentiometer and an output terminal of the said networks, and the arrangement being such that the product of the step-down ratio of said transformer and the ratio of the transfer admittance to the output admittance of said first network, when so connected to said second network, is approximately a pure imaginary quantity.
